UNITED STATES PATENT OFFICE.

PHILLIP COMEAU, OF NEW BEDFORD, MASSACHUSETTS.

SHUTTLE.

1,056,501

Specification of Letters Patent. Patented Mar. 18, 1913.

Application filed September 14, 1912. Serial No. 720,375.

To all whom it may concern:

Be it known that I, PHILLIP COMEAU, a citizen of the United States, and residing at New Bedford, in the county of Bristol 5 and State of Massachusetts, have invented certain new and useful Improvements in Shuttles, of which the following is a specification.

This invention relates to shuttles and particularly to mechanically operating means 10 for threading a shuttle.

An object of the invention is to produce means, manually or otherwise actuated, for delivering thread to an eye of a shuttle or 15 into such relation to the eye, that it may be pulled therethrough.

A further object of the invention is to provide a thread moving member adapted to extend into the eye of a shuttle for carrying 20 the thread; and it is also an object of the invention to provide novel means for causing the thread moving member to travel in the eye.

With the foregoing and other objects in 25 view, the invention consists in the details of construction and the arrangement and combination of parts to be hereinafter more fully set forth and claimed.

In describing the invention in detail reference will be had to the accompanying 30 drawing forming part of the specification, wherein like characters of reference indicate similar parts in the several views and in which—

Figure 1 is a view in elevation of a shuttle containing a mechanism embodying in physical form one type of the invention. Fig. 2 is a perspective view of a fragment 40 of a shuttle illustrating on an enlarged scale an embodiment of the invention. Fig. 3 is a broken sectional view of a fragment of a shuttle and elements of the invention which are also partly in section. Fig. 4 is a view in elevation showing an embodiment of the 45 invention detached from the shuttle. Fig. 5 is an end view thereof.

In these drawings 5 denotes a shuttle, which may be of any type; the same having an eye 6 for the passage therethrough of 50 the thread 7, shown as coming off the spindle 8.

The shuttle may contain means for guiding a thread to a thread moving member and to the end may consist in a guide 55 9, secured, in operative relation, to the thread moving member, and the thread mov-

ing member may take the form of a needle 10, having a shoulder 11 to which the thread is directed by the guide 9. The illustrated embodiment of the invention, also has a 60 guide 12, with a slot or recess 13, to receive the thread. The upper edge 14, of the guide 12 extends diagonally with relation to a line transversely of the shuttle, and it is inclined 65 slightly toward the eye of the shuttle; the inclined diagonally extending edge being provided to facilitate the entry of the thread into the recess 13, since the thread will ride down the inclined edge and enter the recess.

The guide 9, in the illustrated embodiment of the invention, is of peculiar shape and terminates at its lower end below the eye of the shuttle and is anchored to the shuttle by being carried by the plate 15 attached to the shuttle, by the screw 17. The 70 lower end of the guide is reduced in width and its edge tapers and merges with a notched portion 9a of the plate and acts to direct the thread downwardly and into position to be engaged by the thread moving 75 member. The guide 9 is also shown as extending upwardly and diagonally across the shuttle, its edge 16 being adapted to be engaged by the thread, and the outer end of said 80 guide terminates in a tapered head 17a, with its nose 18a extending toward the spindle; in order that in an attempt to pull thread from the spindle and insert it around the 85 guard 9, the head will serve to direct the 90 thread to the proper position.

The thread moving member is, as has been stated, illustrated herein as a needle 10 attached to a lever 18, which lever is mounted on a pivot 19, and the needle is in such position with relation to the eye that it is 95 moved therein when the lever is operated. The exact construction of the needle may be varied but is shown as having a notch 20 forming a shoulder 21 for engaging the thread and carrying it through the eye as 100 the needle is moved in said eye. The end of the lever remote from the needle has a thumb key 22 thereon and said end is bent in order that its surface will contact with the guide 12 and aid in directing the thread 105 to the notch or recess 13 in the guide. A spring 23 is secured to a post 24 and engages an eye 17b of the lever for holding the thumb key on the guide 12.

In operation, a thread is pulled from the spindle and the thumb key is manipulated 110 to swing the lever on its pivot thereby carry-

ing the said thumb key away from the guide which it engages. After the thread has been inserted under the thumb key the thumb key is released and the thread is thereby carried 5 so that it will lie between the thumb key and the guard which it engages. The thread is then passed around the guide 9 by inserting the said thread over the head of the guide between the edge of the head and side 10 of the shuttle containing the eye. After looping the thread around the guide 9 a pull exerted on the said thread results in the looped portion thereof riding down the inclined surface of the edge of the guide 9 15 to the lower end of the guide and in position to be engaged by the shoulder or the eye of the needle, it being understood that during the movement of the thread down the inclined surface of the guide 9, it has also traveled down the inclined surface of the guide 12 and into the notch or recess 9^a in the plate to insure the entrance of the thread into the eye or notch or recess of the needle. When the thread has been caused to travel into such 20 relation to the needle that it may be engaged and moved thereby, the needle is actuated. By pressure on the thumb key, the lever is swung on its pivot and the needle is caused to project into and through the eye, carrying the thread therewith, so that the thread 25 may be grasped and pulled through the eye and the needle may be allowed to return to its normal position under the tension or pressure of the spring on releasing the thumb key.

In further explanation of the operation of the invention, an inspection of Fig. 1 will show the looped portion of the thread embracing the rear edge of the guide 9, and the thread is shown as being without tension. If a pull is exerted on the free end of 40 the thread, the loop will be caused to engage the rear edge of the guide 9, and owing to the inclination, the said thread will travel 45 down the said inclined surface toward the

eye in the shuttle and the thread will eventually descend so far as to pass into the notched portion 9^a of the plate thus causing the thread to descend into the recess 13 in order that said thread may enter the recess 50 of the needle and be engaged by the shoulder thereof when the lever is manipulated for the purpose of actuating the said lever.

I claim—

1. In a shuttle threading device, a shuttle 55 having an eye, a plate secured to the shuttle, a thread engaging member adapted to deliver thread to the eye, a lever for actuating said thread engaging member, a guide having an inclined upper edge provided with 60 a recess, a thumb key for the lever coacting with the guide to confine the thread between the thumb key and the guide, and a guide on the plate having an inclined edge around which the thread is looped and down which 65 it is adapted to travel when pull is exerted on the thread whereby thread is delivered to the thread engaging member in position to be delivered to the eye of the shuttle.

2. In a shuttle threading device, a shuttle 70 having an eye, a plate secured to the shuttle, a thread engaging member adapted to deliver thread to the eye, a lever for actuating said thread engaging member, a guide having an inclined upper edge provided with a 75 recess, a thumb key for the lever coacting with the guide to confine the thread between the thumb key and the guide, and a guide on the plate having an inclined edge around which the thread is looped and down which 80 it is adapted to travel when pull is exerted on the thread whereby thread is delivered to the eye of the shuttle, and means for actuating the lever in one direction.

In testimony whereof, I affix my signature 85 in the presence of two witnesses.

PHILIP COMEAU.
